EGBERT W. SPERRY, OF WOLCOTTVILLE, CONNECTICUT.

Design No. 2,641, dated April 30, 1867.

DESIGN FOR A KNIFE OR FORK-HANDLE, &c.

The Schedule referred to in these Letters Patent and making part of the same.

TO ALL WHOM IT MAY CONCERN:

Be it known that I, EGBERT W. SPERRY, of Wolcottville, county of Litchfield, and State of Connecticut, have produced certain new and useful Pattern or Design for a "Handle" for Knife, Fork, or Spoon; and I do hereby declare that the same is described and represented so as to enable others skilled in the art to make and use the same therefrom, reference being had to the drawings, and letters marked thereon which indicate like parts.

In the accompanying drawings, marked No. 2, *a* is a handle for knife, fork, or spoon. This handle is configurated with double bead or thread, *a' a''*, and embellished with grape-foliation, and cluster at each end thereof, to produce a plain, rich pattern or design for a handle.

What I claim, therefore, and desire to secure by Letters Patent, is—

A design for a handle for knife, fork, or spoon, substantially as shown and described.
